W. B. KIMMEL

STOVE

Filed June 10, 1924

Fig. 1.

INVENTOR.

W. B. Kimmel.

R. J. Bassett

ATTORNEY.

UNITED STATES PATENT OFFICE.

WILLIAM B. KIMMEL, OF SAN FRANCISCO, CALIFORNIA.

STOVE.

Application filed June 10, 1924. Serial No. 719,159.

To all whom it may concern:

Be it known that I, WILLIAM B. KIMMEL, a citizen of the United States, residing at San Francisco, county of San Francisco, and 5 State of California, have invented certain new and useful Improvements in Stoves, of which the following is a specification.

This invention relates to improvements in stoves, and more particularly to portable or 10 knock-down stoves designed for military or camping uses.

On July 2nd, 1907 I obtained Letters Patent No. 858872, which discloses a stove of the type improved by the present invention, 15 and the primary object of this invention is to increase the size or area of the surface of the cooking compartment and to eliminate the liability of burning food cooking in the oven.

Another object of the invention is to provide the fire box compartment of the above 20 mentioned patent with a detachable pipe section arranged, when in use, to feed the products of combustion into the oven chamber and adapted when not in use to occupy 25 the oven chamber, so that the various parts of the stove may be packed in nested relation for transportation purposes.

With the foregoing objects outlined and 30 with other objects in view which will appear as the description proceeds, the invention consists in the novel features hereinafter described in detail, illustrated in the accompanying drawing and more particularly pointed out in the appended claims.

Referring to the drawing:

Figure 1 is a longitudinal vertical sectional view, partly broken away, of the stove parts in assembled relation and ready for use.

Fig. 2 is a perspective view of the improved pipe section and the means for connecting the same to the rear end of the fire box.

Fig. 3 is a horizontal sectional view taken 45 on line 3—3 of Fig. 1.

For the purpose of the following detail description, I am using the same reference characters as are in said patent, wherever this is possible.

In the drawing, 1 designates a firebox, 50 preferably formed of sheet metal and having sides 2, ends 3 and a top 4. The lower end of the firebox is open, so that the fire may be built directly on the ground. The

firebox is provided with a hinged door 55 for the purpose of feeding fuel into the firebox etc.

The rear end 3 is provided with an opening 3^a partially surrounded by flanges 3^b and 3^c, which form a frame adapted to receive 60 a removable pipe section 3^d. This pipe section has a rectangular flange 3^e adapted to 65 slidably fit in the flanges 3^b, 3^c and provided with an opening 3^f designed to register with the aperture 3^a, so that the products of combustion from the firebox will pass out 70 through the pipe section. The pipe section has a closed bottom 3^g so as to cause the products of combustion to pass upwardly. In my patent above mentioned the outlet 75 opening for the products of combustion is placed in the top 4 of the firebox and an annular flange surrounds said opening, so that the oven compartment 9 projected for quite 80 a distance over the upper surface of the top 75 4 and decreased the effective surface which could be utilized for cooking purposes. Owing to the present construction the oven 9 may be located a relatively greater distance from the front end 3 of the firebox, 85 and consequently substantially all of the upper surface of the top 4 of the firebox may be utilized for cooking purposes, that is, to support frying pans, stewing pots, etc.

The oven 9 is especially well adapted for 85 baking and the like, and is formed from sheet iron or some similar suitable material. Like the firebox, the oven is preferably substantially rectangular in form and has a top 10, bottom 11, sides 12 and ends 14 joined 90 in any suitable manner. The bottom 11 is provided with an opening 15 near one end of the oven adapted to register with the upper end of the pipe section 3^d, when the oven is mounted thereon, as clearly shown in Fig. 95

1. To support that part of the oven which is not mounted upon the firebox, I provide the oven with a foldable support or leg 16 pivoted at that end of the oven remote from the opening 15. The support is adapted to 100 rest upon the ground and hold the oven in a suitable horizontal position. The top 10 of the oven has an opening 17 surrounded by an upwardly projected collar 18 adapted to be connected to a sectional stove pipe 19. As 105 in my above mentioned patent, the sections of the stove pipe are designed to be placed in the oven, when the stove is in packed con-

dition. Furthermore, the pipe section 3^a is also of a size suitable to be stored within the oven.

The oven is provided with an inner compartment 23, forming double walls at the top, bottom and ends, with a continuous chamber 24 between these double walls. The compartment 23 extends from one side to the other of the oven, and consequently there are no double side walls or chambers at the sides. One of the side walls of the oven is provided with the usual door, (not shown). The hot gases from the fire escape from the firebox through the opening 3^a and pipe section 3^a into the chamber 24, circulate therein and find an outlet through the opening 17 and the smoke pipe 19. It will be understood that in this way the oven is completely surrounded by the products of combustion, and owing to the fact that these products of combustion must pass through the pipe section 3^a, they will not be as hot as if they enter the chamber 24 directly from the firebox, as in my prior patent, and consequently there will be less danger of burning food in the oven.

For the purpose of causing the products of combustion to pass entirely around the compartment 23, I provide a damper 28, consisting of a flat plate having a laterally disposed end, which is adapted to slide on the top of the inner compartment 23, and to close the opening between the upper part of the chamber 24 and the front end of said chamber, which is arranged over the pipe section 3^a. The damper is provided with the usual handle 29, which projects through an opening 30 in the end of the oven.

In order to pack the stove for storing or shipping, the smoke pipe 19 is removed and separated into its sections. These sections, together with the pipe section 3^a, are placed within the compartment 23 of the oven. The oven 9 is then detached from the firebox, and the support 16 is folded upwardly against the left hand end of the oven, and then the oven is placed through the opening at the bottom of the firebox 4, after the latter has been inverted.

From the foregoing it is believed that the construction and advantages of the invention may be readily understood and it is ap-

parent that changes may be made in the details disclosed without departing from the spirit of the invention as expressed in the claims.

55

What I claim and desire to secure by Letters-Patent is:

1. A portable stove for camping purposes and the like comprising a firebox having a cooking top, an open bottom and a substantially vertical wall, said wall being provided with an outlet opening to discharge the products of combustion, an upwardly extending pipe section detachably connected to said wall and having an opening registering with said outlet opening, an oven having one of its ends projecting only slightly over and resting on the cooking top of the firebox, the bottom of said oven having an opening into which the pipe section extends for discharging products of combustion into the oven, said oven having a baking compartment of sufficient size to house said pipe section when the latter is detached from the firebox, and the oven being of such size as to be nested in the firebox when the stove is not in use.

65

2. A portable stove comprising a substantially rectangular firebox having a cooking top and a vertical end wall, an outlet port in said end wall, a frame arranged on the end wall and partially surrounding said port, a pipe section having a frame adapted to slidably engage the frame on the end wall of the firebox and provided with an opening adapted to register with said port, said pipe section having a closed bottom and an open top, the latter projecting above the cooking top of the firebox, a substantially rectangular oven adapted to be nested within the firebox and having an opening arranged in close proximity to one of its ends and adapted to receive the upper end of the pipe section, said oven having a cooking compartment of a size to house said pipe section when the latter is detached from the firebox, one end of the oven resting directly on the cooking top, and an auxiliary support for the other end of the oven.

70

In testimony whereof I hereunto affix my signature.

WILLIAM B. KIMMEL.
